HORN

Filed April 9, 1925

UNITED STATES PATENT OFFICE

MERWIN F. ASHLEY, OF CHICAGO, ILLINOIS

HORN

Application filed April 9, 1925. Serial No. 21,776.

My invention relates to horns for amplifying sound waves.

The object of my invention is to provide a horn of semireflex type that will be free 5 from synchronous vibrations of the sounds being transmitted therethrough.

A further object is to provide a horn, all the parts of which may be cast or molded into the desired form, and easily united to 10 provide a horn of this type at a low cost.

A further object is to provide a horn having a long air column in a small space.

Referring to the drawings which form a part of this specification.

15 Fig. 1 is a front elevational view of a horn embodying my invention.

Fig. 2 is an inner side view of one half-portion of the device.

Fig. 3 is a cross sectional view of the 20 device taken on line 3—3 of Figure 2.

The body portion of the device comprises the two parts A and A' respectively, each of which is cast or molded of suitable material to provide a horn that will emit no 25 audible tone due to vibration of the material used in its construction.

I prefer to make the horn of sawdust or shavings, or a mixture thereof, held together by a thin glue solution or other suitable cement such as silicate of soda, and molded in 30 a form under pressure. I may however, make the horn of any other suitable material such as china clay, kaolin, etc. or of wax composition.

35 A² indicates the inner side wall of the side portion A and formed with a plane surface which is adapted to contact with a similar plane surface formed on the opposite side portion A'. Both side portions A and A' are formed to provide a conduit for sound waves indicated by B, and hereinafter referred to as the throat, and an outlet in open communication with the throat, indicated by C, and hereinafter referred to as 40 the bell.

The opposite sides B' of the wall of the throat B therefore comprise and form a part of the inner side of the wall of the bell C as shown by Fig. 1 of the drawing. In other 45 words the throat is formed by two half por-

tions, in the opposed faces A² of each section A, A' with the exit opening located at a point in advance of the rounded end of the bell.

Each portion A and A' may be provided 55 with holes D—D—D respectively to receive dowels E which help to hold the parts together and also to position them correctly. The dowels may be dispensed with, if desired, when the said portions are cemented 60 together with strong cement.

The base portion F may be formed integral with the globular portions as illustrated, or may be formed separately and cemented or otherwise suitably connected to 65 the said portions. A tube G is inserted in the lower end of the throat B and projects into a chamber H formed in the base F, to which the speaker-unit I is connected in the usual manner. The throat B extends upwardly from the tube G in a curve formed like a question mark, to a point above the bell C and then opens into the bell at a short distance from the inner end C' thereof as shown. The parts heretofore 70 described when united provide a complete 75 horn which may be successfully used.

I prefer however to cover the surfaces both inside and outside with a hard smooth enamel A⁴ which improves both the appearance and tonal quality of the horn. A further improvement is provided by placing a glass or porcelain lining J in the bell and firmly cementing it in place therein as illustrated. If greater amplification is desired, 80 an extension horn K, indicated in dotted lines, may be inserted in the bell in detachable relation therewith, or the lining J and parts K could be formed in one piece if desired. By making the walls thick, and of 85 material such as described, the tones generated by the transmitting station are reproduced in the horn without introducing harsh or discordant tones due to vibrations set up in the material of which the horn is made. 90 By forming the opening L at a distance 95 from the inner end of the bell C', as illustrated, no sound is reflected from the surface of the bell back into the throat or passage B, and therefore, the full volume of sound re-

ceived is reflected in the bell and projected directly therefrom, and all of the advantages of the reflex type of horn is provided without the defects inherent in said types.

Having thus described my invention, I claim as new:

1. A horn comprising a massive body portion having thick walls and recessed to form a bell and having a throat formed therein extending from the lower surface of said body portion and opening into said bell at its upper side.
2. A horn comprising a massive body portion having thick walls and having a throat and a bell formed therein, portions of said throat and bell having a common wall.
3. A horn comprising a massive body portion having a throat and a bell formed therein, a portion of said throat and a portion of said bell having a common wall, said throat and bell having a lining of vitreous material.
4. A horn comprising a massive body portion having thick walls and a throat and a bell formed therein at a point forwardly of the inner end of the bell.
5. A horn comprising a massive body portion having thick walls recessed to form a bell and having a throat formed therein extending from the surface of said body portion and opening into said bell at a point forwardly of the inner end of said bell.

In testimony whereof, I, MERWIN F. ASHLEY, have signed my name to this specification this thirtieth day of March, 1925.

35 MERWIN F. ASHLEY.
